[57] CLAIM

The ornamental design for an examination table, as shown.

DESCRIPTION

FIG. 1 is a perspective view of an examination table showing our new design in reclined position;

FIG. 2 is a side elevational view thereof;

FIG. 3 is a top plan view thereof;

FIG. 4 is a left side elevational view thereof, as viewed from FIG. 1;

FIG. 5 is a right side elevational view thereof, as viewed from FIG. 1; and

FIG. 6 is a perspective view thereof, in raised and extended position.
